UNITED STATES PATENT OFFICE.

CYRUS KEHR, OF CHICAGO, ILLINOIS.

FIRE-ESCAPE.

SPECIFICATION forming part of Letters Patent No. 291,601, dated January 8, 1884.

Application filed February 27, 1883. (No model.)

To all whom it may concern:

Be it known that I, CYRUS KEHR, of Chicago, in the county of Cook and State of Illinois, have invented certain new and useful Improvements in Fire-Escapes; and I do hereby declare that the following is a full, clear, and exact description thereof, reference being had to the accompanying drawings, and to the letters of reference marked thereon, which form a part of this specification.

This invention relates to ladder fire-escapes, and may be referred more particularly to that class of said escapes which are permanently attached to the exterior of large buildings, such as hotels, mercantile houses, and manu-

factories.

The objects of the invention are to provide a permanent fire-escape which will fulfill several conditions necessary to be fulfilled in order to attain the greatest efficiency. These conditions are as follows: First, the escape must afford a passage from the building to the ground, and standing-places for firemen, both at a considerable distance from said building, in order that persons escaping from the building when on fire, and firemen fighting the fire from positions on said escape, will be, as much as is practicable, out of the reach of the heat, flames, smoke, and falling brands or other objects issuing or falling from such building, and from the current of heated air rising next to the building, thereby rendering such escape available for use a much longer time than is the case when such passage and standing-places are close to the wall; second, the escape must afford standing-places from which the firemen can direct streams of water into either of several adjacent windows without changing position; third, the escape must be adapted to be so disposed, when not in use, as to be out of the way and inaccessible from the ground, and as not to produce an objectionable effect on the appearance of the building to which it is attached; fourth, the escape must be so simple in construction and operation that it may always be changed from its position of rest to its position for use without complication or delay; fifth, the escape must be provided with simple means for effectually freeing it of snow and ice when the latter are deposited upon it.

To these ends the invention consists in the matters hereinafter described and set forth, and particularly pointed out in the claims.

I am aware that certain forms of folding-

ladder escapes have heretofore been attached to buildings. For example, ladders having their rounds hinged to the uprights, so as to make a collapsible ladder, have been set at right angles to and with one side fixed permanently against the building, the ladder being collapsed (that is, the free upright swung upward and inward against the fixed one) when not in use. A ladder compounded of two ladders like the last above mentioned has also been constructed, two side rails being attached to the building close to each other, and the rungs of one inclined toward those of the other, and connecting with a common free side rail, which latter, upon folding, lies against the wall midway between the two fixed side rails. A rigid vertical ladder has also been set at right angles to and against the wall and hinged thereto in such manner as to allow the ladder to rotate horizontally on its inner side rail and lie flatwise against the building. A folding escape has also been made having a series of horizontal platforms extending along the wall beneath the windows, and hinged to turn upward flatwise against the wall, each of such platforms having a central hatchway, from the outer side of which an independent section of ladder is hinged, and extends obliquely inward and downward almost to the platform next below, at which point it is linked to the wall, said section being adapted to fold against the building with the platforms. Ordinary fixed balconies have also been arranged along a wall in a vertical series and connected with each other by oblique independent ladder-sections, each of the latter being adapted to fold upward against the balcony next above it; but it will readily appear that these differ from my invention, in that in these the ladders are permanently in contact with or close to the building.

In the ladders described as being continuous one side of the ladder rests permanently against the building. In the escape having the folding platforms the lower end of each ladder-section rests practically against the wall. Moreover, it would be objectionable to so construct this escape as to place even the upper ends of the ladder-sections as far from the building as I propose to place my entire ladder, for the reason that to pass the ladder-sections through a hatchway in the folding platform necessitates the use of a wide platform, and if the platform is wide it must not

be made long, else it will cover too much of the wall, and will in many situations partially cover the windows. In my escape the bridges to be described need be no wider than the ladder itself, and may therefore be of any desired length. It will also be seen that my escape differs further from the one to which I have just made reference, in that in the latter the ladder-sections, when folded, are partly or wholly covered by the platforms when the escape is folded, while in my escape the ladder is not covered by any of the other parts, which will be hereinafter shown to constitute an important feature. In the case of the fixed balconies the entire sections must be set close to the wall, for the obvious reason that it would be objectionable and impracticable to extend fixed balconies far enough outward from the wall to allow the ladder-sections to be placed at any considerable distance from such wall. I do not, therefore, lay claim to a fire-escape having a ladder which merely folds or collapses, but is practically stationary and not designed to be shifted bodily a material distance from the building for the purposes above mentioned.

I am also aware that it is not new to use a stand-pipe as an upright in a ladder, and do not, therefore, claim the same as my invention.

In the accompanying drawings, Figure 1 is a perspective view of a building provided with two of my improved escapes, one standing in position for use and the other folded against the building. Fig. 2 is a detail perspective view of a preferred form of the passage-ways between the ladder and the building. Fig. 3 illustrates a counter-balance for holding the ladder against the building. Fig. 4 shows an oblique ladder-section extending from the upper end of the main ladder to the roof. Fig. 5 is a front elevation, partly in section, of a hinge pipe-coupling used to join the pipe of the main ladder to that of the short section leading to the roof. Figs. 6, 7, and 8 illustrate a folding platform on the outside of the main ladder. Fig. 9 shows a ladder constructed for melting the ice therefrom by means of steam.

Referring to said drawings, A is a vertical ladder, set at a suitable distance—say ten or fifteen feet—from a building, C, and in a plane parallel to the adjacent wall of said building.

A' is a stand-pipe, shown as constituting one of the uprights or side rails of the ladder.

A² is the opposite upright, and a a are the rounds of the ladder.

The stand-pipe A', when used, is provided at or near its lower end with an inlet and coupling device, as a', for the attachment of hose from the fire-engines, and along its sides and upper end it has valved outlets a² a² and means for attaching hose at such outlets. The rounds a a and the upright A² may extend downward even with the lower end of the stand-pipe A'; or the lower portion of the latter may be left naked, as shown in Fig. 1. The object

of the latter construction is to make the ladder, when folded, inaccessible from the ground in case it is not lifted upward far enough in folding to otherwise place the end thereof out of the reach of persons standing on the ground. I prefer to have the base of the ladder, when in position for use, rest on the ground, the weight of the ladder and most of the parts connected therewith being supported on such base. When the ladder is thus supported, and the lower end of the stand-pipe is continued beyond the lower end of the ladder, as above set forth, said naked end of the stand-pipe should be bent laterally toward the vertical line of center of the ladder, as shown in Fig. 1, so as to bring the point of support within said line of center; but said ladder may, if so desired, be supported from the wall, and not allowed to quite reach the ground. The ladder may be joined to the building in various ways, and I do not limit myself to the means shown below. The construction shown is preferred, as being simple and economical.

B B are horizontal links, hinged by their ends to the ladder A and the wall of the building C. Said links may be plain rods or bars, and may be arranged either in pairs or singly. If rod or bar links are used, it is best to arrange them in pairs, as shown in Fig. 1, the outer ends thereof being hinged one to each of the uprights A' A², and by preference diverging somewhat from thence to the wall, one pair being about opposite the base of the adjacent window or windows, D, and another pair being placed, say, three or four feet higher, in order that the two on either side may together constitute a bridge and rail for the escape of occupants of the building from the windows to the ladder and for the passage of firemen to and from the building. A preferred form of such bridge is illustrated in Fig. 2. It is there shown as being composed of a broad frame-link and two rod-links, located one on either side of and a short distance above said frame-link, said rod-links constituting the railings and said frame-link the floor of the bridge. Said frame-link may be of any kind of flat horizontal structure hinged by its outer end to the ladder and by its inner end to the wall, and of sufficient strength to support the weight of one or more persons. In said figure the frame or floor-link is shown as consisting of two side rods, B' B', two end rods, B² B², and an intervening structure of coarse wire-netting, B³. The wire-netting makes a comparatively light and yet sufficiently strong floor, and is less conspicuous when folded against the building, and less likely to retain accumulations of snow and ice between itself and the building than a solid floor would be. This form of bridge affords a safe passage between the building and the ladder, and also constitutes an excellent standing-place for the firemen while directing streams of water into the adjacent parts of the building. Said links and bridges need not, however, be identical. Folding bridges may

extend from the wall to the ladder without being so connected with the ladder as to be supported by it. Indeed the bridges need not be joined to the ladder at all, but may be swung 5 from the wall of the building after the manner of a draw-bridge.

In order that the above-described bridges or passage-ways may be more easily accessible from the windows nearest thereto, said windows 10 may be provided with ordinary permanent balconies, D', as shown in Fig. 1.

It is obvious that, if so desired, the ladder may be set directly opposite a vertical series 15 of windows and the inner ends of the bridges be made to meet the bases of the windows, so that a person passing out of one of said windows will at once land upon the bridge opposite such window. This would, however, be objectionable in many cases, for the reason 20 that the escape, when folded, would obstruct the windows, and would also be accessible from only one series of windows, whereas when set between two series of windows it is accessible from each of such two series.

Different means of raising and securing the ladder against the building may be used. For 25 example, a windlass and chain may serve to hoist and a ratchet to secure it, and from the ratchet a cord may depend, by means of which 30 said ratchet may be disengaged; or the ladder may be hoisted by hand and secured by any suitable catch and provided with means for disengagement. I prefer, however, to use a suitably-disposed counteracting weight or 35 spring, (or a set of either,) which shall exert sufficient lifting-power on the ladder, after it has been hoisted upward, say, half-way, or thereabout, by hand or other means independent of such weight or springs, to draw and hold 40 it against the building. In Fig. 3 I show such a weight designated by the letter E. It is connected with the ladder A by a chain or rope, E', running over an elevated fixed pulley, E''. It will be observed that if such weight E is, 45 for example, about half as heavy as the ladder A it will not of itself be sufficient to lift said ladder when set out on the ground; but after said ladder has been raised by hand or otherwise until a little more than half its weight is supported on the links B B, the weight E will draw 50 the ladder to the building and hold it there. This constitutes a complete hoisting and securing mechanism. It requires no special securing or disengaging devices, and the weight 55 E and chain E' are not designed to be acted upon directly by the occupants of the building, as is done in the case of some old devices. On the contrary, said chain and weight are to be so disposed as to be as much out of the way 60 and out of sight as may be.

The manner of setting the escape out in position for use is as follows: One or more of the 65 occupants of the building mount the ladder from an adjacent window or windows, and by their weight overcome the force of the weight E, and the combined weights of the persons

and the ladder draw the escape outward and downward until it rests on the ground. The person or persons on the ladder may materially expedite such outward movement by 70 pushing against the wall with one foot, thereby giving the ladder an impetus which will speedily carry it beyond the balancing-point. Should there be no one within the building to set the ladder out, it may be mounted from the 75 ground by means of a short ladder, or it may be drawn out by means of a hook.

If provision is to be made for communication between the ladder A (whose upper end will usually reach no higher than the uppermost bridge) and the roof of the building, I propose to use an oblique section of ladder extending from the upper end of ladder A to the roof. Such a section is represented by G in Fig. 4. It may be a link or chain ladder 80 attached permanently by its ends to the ladder A and the edge of the roof of the building C, and adapted to collapse and fold with ladder A when the latter is folded against the building. It may also be a rigid ladder hinged to 85 the top of ladder A by its lower end, and having its upper end resting loosely in a guide, G', at or near the edge of the roof, and arranged to slide upward and rest on the latter when the escape is folded. When the rigid section 90 is used, it may be provided with a water-pipe, G', similar to pipe A' in ladder A, the adjacent ends of said pipes being united by any suitable flexible joint, G''. A form of such joint 95 specially adapted to this situation is shown at Fig. 5. The end of pipe A' is bent laterally at right angles to its length and within the plane of the ladder A. The adjacent end of pipe G' is bent laterally at right angles to its length, but in the direction opposite to that of the end of the pipe A' and in the plane of ladder G. The ends of the pipes are exteriorly threaded and run oppositely into the interiorly-threaded thimble, g, until they meet, 100 said thimble being by preference seated immovably upon one of said pipe ends. It is the design to so adjust the threads of the thimble and pipe ends as that said ends will be screwed tightly together when the escape is set out for use, and slightly unscrewed when the escape 105 is folded. As further security against leakage, an annular elastic packing, g', may be inserted between the ends of pipes A' and G', such packing being compressed when the escape is set out.

H, Figs. 6, 7, and 8, is a small platform on the outer side of the ladder A, designed as a standing-place for a fireman in case he does not want to stand on one of the bridges B. Said platform has a pair of hooks, h h, at its 110 inner end, arranged to engage the side rails, A' A'', or a rung, a, and lie loosely on a rung, a. The outer side of the platform H is supported by a pair of oblique rods, h' h', hinged by their upper ends to said platform and by 115 their lower ends to a rung, a, or to the uprights A' A''. When not used, this platform 120

is pushed through the ladder A and allowed to hang in a vertical position on the inner side of said ladder, as shown in Figs. 7 and 8.

Fig. 9 illustrates a method of and means for freeing the escape of ice and snow. One or both of the side rails, A' A'', of the ladder are made of piping, and fitted for the connection of a steam-supply pipe, as at I. The introduction of steam will readily raise the temperature of the ladder and the parts connected therewith above the freezing-point. The most effective method of thus using steam is to pass it upward through one upright and downward through the other. The ladder shown in Fig. 9 is constructed for using this method. The steam passes upward through pipe A'', and at its upper end through a connecting-pipe, J, into pipe A', and down the latter to a return-pipe leading to the boiler-plant. When the pipe A' is a stand-pipe, the connecting-pipe J is provided with a cut-off valve, j, and a short outlet-pipe, K, having a cut-off valve, k, is placed near the lower end of pipe A', the ends of said pipe being closed with caps. These valves are to be closed when the stand-pipe is to be used for conducting water.

Some person having the care of the building should promptly melt the ice off the escape whenever it accumulates, in order that the escape may be ready for use at any time.

I claim as my invention—

1. In a fire-escape attached permanently to a building, a continuous upright ladder constructed to rest closely against such building when not in use, and to be shifted bodily to a material distance therefrom when it is to be used, substantially as herein set forth.

2. In a ladder fire-escape adapted to be set at a distance from or shifted against the building, the combination of the ladder A and links B, hinged to such ladder and building, and arranged to move with such ladder in a vertical plane, substantially as shown, and for the purposes specified.

3. The combination, with a continuous vertical fire-escape ladder, A, adapted to be folded against or set at a distance from the building with which it is connected, substantially as herein described, of folding passage-ways leading from the building to the ladder, substantially as set forth.

4. In a fire-escape having a continuous shifting ladder, the combination, with said ladder, of broad links and pairs of rod-links B, arranged with reference to each other as described, and hinged to the ladder by their outer ends and to the building by their inner ends, substantially as described, and for the purposes set forth.

5. The arrangement of a balcony, D', folding bridge B, and ladder A in such relation to each other and to a window, D, as to form a continuous passage from the latter to the ground, substantially as shown and described.

6. The combination, with an escape-ladder adapted to be shifted to a distance from the building, and to be mounted from the windows

when resting against the building, as herein described, of a counter-balance the force of which is sufficient to hold the ladder, when folded, against the building, but which is not sufficient to resist the weight of the ladder when moved from the wall or when a person mounts said ladder, thereby adapting said ladder to be set into position for use by being mounted by a person from the building, substantially as described.

7. The combination, with a folding ladder-escape adapted, when folded, to be mounted from the building, as herein described, of the weight E, chain E', and pulley E'', said weight E holding such relation to the weight of the ladder as to be overcome when a person mounts the ladder when the escape is folded, substantially as shown, and for the purposes specified.

8. In a folding fire-escape having a vertical ladder, A, and a shorter ladder-section, G, leading from the ladder A to the roof, the combination, with said ladders, of pipes A' and G', hinged together in any suitable manner at their meeting ends, substantially as and for the purposes set forth.

9. In a folding fire-escape having a jointed stand-pipe, a joint formed by bending the meeting ends of the sections of such pipe laterally and inserting them oppositely into a sleeve and securing them therein, substantially as herein shown and described.

10. The combination, with the ladder A, of a platform, H, and braces h', said braces being hinged by their ends to the ladder and the outer side of the platform H, and said platform H being adapted to slide through the ladder A and lie against the inner side of said ladder, substantially as shown and described.

11. In a fire-escape having a non-collapsible ladder constructed wholly or in part of metallic piping, the combination, with said piping, of a coupling device or devices for connecting a supply-pipe from a steam generator or its equivalent, substantially as and for the purpose set forth.

12. The method of freeing a ladder fire-escape of snow and ice, consisting of passing steam or its equivalent upward through one side rail of the ladder and downward through the other, substantially as herein set forth.

13. In a fire-escape ladder having hollow side rails, one of which is a stand-pipe, the combination, with said side rails, of a valved connecting pipe, J, substantially as and for the purposes set forth.

14. In a ladder fire-escape having hollow side rails, one of which is a stand-pipe, and the two communicating at or near their upper ends by means of the pipe J, the combination, with said stand-pipe, of a valved outlet, K, substantially as and for the purposes set forth.

In testimony that I claim the foregoing as my invention I subscribe my name hereunto in the presence of two witnesses.

Witnesses: CYRUS KEHR.
